CLAIM

The ornamental design for a mobile phone flash, as shown and described.

DESCRIPTION

FIG. 1 is a perspective view of a mobile phone flash showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The broken lines in the drawings depict portions of the mobile phone flash that form no part of the claimed design. The dash dot dash lines in FIG. 2 and FIG. 9 are for the purpose of depicting areas of enlargement to show details and form no part of the claimed design.
